UNITED STATES PATENT OFFICE.

ALFRED ARCHER, OF CALDWELL, NEW JERSEY, ASSIGNOR TO MERGENTHALER LINOTYPE COMPANY, A CORPORATION OF NEW YORK.

QUAD BLOCK FOR SLUG-CASTING MACHINES.

Application filed October 6, 1926. Serial No. 139,791.

My invention relates to slug casting machines, such as linotype machines of the general organization represented in United States Letters Patent to O. Mergenthaler, No. 436,582, wherein a slug or linotype is cast in a slotted mold against an assembled line of matrices, which produce the type characters thereon.

Ordinarily the line is composed of a series of individual matrices which circulate through the machine, but at other times, it is made up of a single non-circulating matrix known in the art as a "quad block" and used particularly for the production of rules, border slugs and the like. As commonly constructed the quad block consists of a solid body portion, similar in cross-section to the ordinary linotype matrix, and having in its front face a matrix slide containing the formative cavities corresponding to the characters to be produced. These slides are usually of an integral nature and interchangeable with other slides bearing different characters, it being the custom to remove the slide from the block when it is desired to cast a slug of different form and replace it with another containing the desired formative cavities. It will readily be understood that, as a result of this practice, a wide selection of slides must be kept on hand in order to meet the requirements in the many different classes of work and that, since the slides are an engraved product, and in the majority of cases specially designed, considerable expense is involved. This objection becomes more pronounced in connection with blank forms and tabular work, wherein so many variations in the arrangement and spacing of the lines are required.

The present invention is intended to avoid the above objections and contemplates a matrix arrangement which, while extremely inexpensive, will provide an almost unlimited selection of line spacings and cross-line combinations. To this end, specifically, it is proposed to make up the quad blocks of separate and independent sections, such as the regular linotype matrices and spacing quads, and to fasten the sections together by a removable rule strip which will permit their rearrangement and interchange as desired.

In the accompanying drawings I have shown my invention merely in preferred form and by way of example, and it should be noted that many changes and variations

may be made therein and in its mode of adaptation, which will still be comprised within its spirit. Generally speaking, I desire it to be understood that I do not wish to limit myself to any specific form or embodiment, except in so far as such limitations are specified in the claims.

Referring to the drawings:

Fig. 1 is a front or face view of a quad block constructed according to the present invention;

Fig. 2 is an end view thereof;

Fig. 3 is a perspective view of one of the matrix sections employed;

Fig. 4 is a perspective view of the rule strip;

Fig. 5 is a sectional view showing the quad block in casting position;

Fig. 6 shows a blank or ruled form illustrative of the class of work for which the present invention is particularly designed; and

Fig. 7 shows a portion of two slugs cast from different quad blocks.

As shown in Figs. 1 and 2 the improved quad block A comprises an assemblage of matrix sections A¹ and blank or spacing sections A² held together by a long binding strip B, which is passed through all of the sections from one end of the block to the other, but which is capable of removal at will to permit the rearrangement or interchange of the sections when desired. The matrix and blank sections are each formed with upper and lower pairs of projecting ears a to adapt the block for support and alignment in commercial linotype machines in the regular way and also with a dovetailed notch a' of the proper size to accommodate snugly the binding strip B. In the embodiment illustrated the sections A¹ A² are constituted by the standard line or leader matrices and spacing quads employed in the commercial linotype machine, although the distributing teeth a² and font notches a' with which they are provided are unimportant, and have no particular utility in so far as this invention is concerned.

The line formative cavities a² of the matrix sections A¹ are disposed vertically or longitudinally thereof and form a series of transverse ribs or ruling surfaces c on slugs C cast therefrom (see Fig. 7), and when lines of any extent are desired, a number of these slugs will be cast from the same matrix.

line and then assembled, side by side, to bring the ribs c into transverse alignment. Fig. 6 which shows a ruled form, gives an illustration of the kind of work which the present invention is intended to produce, it being noted that a series of horizontal broken lines D^1 are in effect intersected by a series of vertical solid lines D^2 . The horizontal lines D^1 are produced by the transverse ribs c of the assembled slugs, the spacing of the lines corresponding to the arrangement of the matrix sections A^1 and blank section A^2 which make up the quad block A. It will be noted that these sections are identical, except as to thickness, and consequently lend themselves readily to handling, selecting and storage. Furthermore, by the use of the standard linotype matrix and spacing quad, a vast selection of sizes is available to provide the many variations in the line spacings required.

In order to produce the vertical lines D^2 of the ruled form D, the quad block A is provided with a continuous line or rule 25 formative cavity B^1 disposed horizontally or longitudinally of the block and thus at right angles to the matrix cavities a^2 . In the preferred embodiment illustrated, the cavity B^1 is formed in the exposed face of the binding 30 strip B, although it could be formed in the matrices and quads themselves if the strip B were positioned differently, or other means were provided for holding the sections together. This latter alternative, however, 35 would involve considerable extra expense, since each individual section would have to be put through extra routing and punching operations.

It will be noted that the relative position 40 of the dove-tailed notches a^1 , and the matrix cavities a^2 is such as to enable the rule cavity B^1 to be located in immediate juxtaposition to the matrix cavities, so that both may be cast on the same slug when the block is presented to the mold (see Fig. 5). Such a slug 45 is indicated at C^1 in Fig. 7 and, as shown, it is formed with a longitudinal ruling rib c^1 as well as with the transverse ribs c , the rib c^1 being cast on one edge of the slug rather than being spaced inwardly therefrom, in order that the transverse ribs c of an adjacent 50 slug may come substantially flush against the rib c^1 and cause the breaks at the intersecting points of the lines D^1 D^2 to be almost imperceptible in the printed form.

In providing for variable spacing of the vertical lines D^2 , it is proposed to cast the slugs of different thicknesses, with or without the longitudinal ribs c^1 , and utilize the 55 slugs without the ribs c^1 to separate the others. In this connection it will be observed (see Fig. 5) that while the rule cavity B^1 is sufficiently close to the matrix cavities a^2 to serve in the manner described, there is still ample space allowed for the casting of a

thinner slug C (Fig. 7) against the block, which will have only the transverse ribs c on its printing edge. At such times, of course, the cap of the narrower slotted mold employed will shut off the cavity B^1 (as indicated by the broken lines in Fig. 5).

In selecting the matrices for any particular job, the spacing of the vertical lines D^2 should preferably determine the height of the matrix characters. In other words, the spacing between the vertical lines should correspond to the height of the matrix characters, or a multiple thereof, so that the slugs without the longitudinal ribs c^1 may be employed to separate the lines the required distance apart and, of course, without involving the use of different quad blocks for the casting of the different slugs. It is also advisable to maintain the same relation between the formative cavities 85 of the matrices A^1 and the strip B, irrespective of the size or height of the matrix characters. The position of the dove-tailed notch a^1 in the casting edges of the matrices and quads will be varied accordingly.

As before stated, I have shown my invention only in preferred form and by way of example, but obviously many changes and variations may be made therein and in its mode of adaptation without departure from its scope. I, therefore, desire it to be understood that I do not wish to limit myself to any specific form or embodiment, except in so far as such limitations are specified in the 95 claims.

Having thus described my invention, its construction, and mode of operation, what I claim and desire to secure by Letters Patent of the United States is as follows:—

1. A quad block for producing a ruled form, comprising a series of independent matrix sections, a series of independent blank spacing sections, and a binding strip for holding the sections together as a unit.

2. A quad block for producing a ruled form, comprising a series of independent matrix sections, a series of independent blank spacing sections, and a binding strip for holding the sections together as a unit, said strip being removable at will to permit 110 rearrangement or interchange of the sections.

3. A quad block for producing a ruled form, comprising a series of independent matrix sections having line formative cavities, a series of independent blank spacing sections, and a binding strip countersunk in the casting edges of the sections to hold them together as a unit and itself provided with a line formative cavity.

4. A quad block for producing a ruled form, comprising a series of independent matrix sections, a series of independent blank spacing sections, and a binding strip for holding the sections together as a unit.

and provided with a line formative cavity located adjacent the formative cavities of the matrices so as to serve conjointly therewith as described.

5. A quad block for producing a ruled form, comprising a selection of independent matrix and independent blank spacing sections formed with recesses in their casting edges, and a longitudinal binding strip passing through all of the recesses from one end of the block to the other for holding the sections together as a unit but capable of removal to permit rearrangement or interchange of the sections, as desired.
10. The method of constructing a quad block for producing a ruled form, which consists in providing a selection of independent linotype matrices and independent spacing quads, arranging said matrices and quads in the desired order, stacking them face to face with their recesses aligned, and inserting a binding strip in the continuous groove presented by the aligned recesses to hold the units of the stack together.
15. The method of constructing a quad block for producing a ruled form, which consists in providing a selection of independent matrix sections, formed with vertically disposed line producing cavities, and a binding strip passed through said matrix sections to hold them together as a unit, and formed alone with a horizontally disposed rule producing cavity.
20. sired order, stacking them face to face to align the matrix characters, and then binding them together in a composite unit.

7. The method of constructing a quad block for producing a ruled form, which consists in providing a selection of independent linotype matrices and independent spacing quads, each formed with a recess in its casting edge, arranging said matrices and quads in the desired order, stacking them face to face with their recesses aligned, and inserting a binding strip in the continuous groove presented by the aligned recesses to hold the units of the stack together.

8. A quad block made up of a series of independent matrix sections, formed with vertically disposed line producing cavities, and a binding strip passed through said matrix sections to hold them together as a unit, and formed alone with a horizontally disposed rule producing cavity.

In testimony whereof, I have affixed my signature hereto.

ALFRED ARCHER.
